UNITED STATES PATENT OFFICE.

TRUCKSON S. LA FRANCE, OF ELMIRA, NEW YORK.

UPRIGHT TUBULAR STEAM-BOILER.

SPECIFICATION forming part of Letters Patent No. 487,124, dated November 29, 1892.

Application filed June 10, 1892. Serial No. 436,208. (No model.)

To all whom it may concern:

Be it known that I, TRUCKSON S. LA FRANCE, of Elmira, in the county of Chemung and State of New York, have invented a new and useful Improvement in Upright Tubular Steam-Boilers, of which the following is a full, clear, and exact description.

Reference is to be had to the accompanying drawings, forming a part of this specification, in which similar letters of reference indicate corresponding parts in all the figures.

Figure 1 of the drawings represents a vertical section of an upright tubular steam-boiler embodying my invention; Fig. 2, an inverted plan of the same, and Fig. 3 a horizontal section taken upon the irregular line $\alpha\alpha$ in Fig. 1.

One of the objects of the invention is to keep the upright fire or smoke flues of the boiler mainly or wholly submerged in the feed-water of the boiler to better protect them without choking the steam-space of the boiler with water.

Another object of the invention is to improve the circulating and heating capacity of the boiler and to prevent injurious exposure of the bottom or crown sheet in case of supply of feed-water to the upper water-space of the boiler being stopped or interfered with.

Other results are also secured by the invention which contribute to the general efficiency of the boiler.

The invention consists in certain novel constructions and combinations of parts, whereby said results are very perfectly secured, substantially as hereinafter described, and more specifically pointed out in the claims.

A indicates the outer shell of the upright tubular steam-boiler of cylindrical shape and constructed to form a water-jacket *b* below surrounding the fire-chamber *B* and with a perforated distributor *c* at top for the more equal supply of the steam from the steam space or chamber *C* of the boiler surrounding the smoke-flues *d*, indicating the steam supply or escape pipe.

D are the upright smoke-flues connected as usual or in any suitable manner with and opening through the lower flue or crown-sheet *e* and upper flue-sheet *f*.

E indicates by dotted lines the smoke pipe or chimney, and *F* a distributor depending

from the crown-sheet *e* and serving to equalize the flame and gaseous products of combustion passing to the flues *D* and to spread them, so as to act upon water circulating and heating legs *G*, connecting the water-jacket *b* below with the space immediately above the crown-sheet *e*. These water circulating and heating legs *G* are composed of or have combined with them a group of surrounding upright tubes *g*, fitted with circulating-tubes, as diaphragms *h*, within them, to give greater heating capacity and more perfect circulation of the water.

Inclosing the smoke-flues *D* and extending up from the crown-sheet *e* to near the top of said flues, more or less, is an overflow-jacket *H*, which may be held in position at its proper distance from the flues by a ring-like skirt *i*, mounted on the crown-sheet and provided with perforations *k* all around it. With this overflow or smoke flue submerging jacket *H* or with the perforated skirt *i*, over which said jacket fits, the feed-water pipe *l* to the boiler connects. This causes the water as it is fed to the boiler to pass within the jacket *H* and so as to protect the smoke-flues *D* by keeping them submerged for the greater portion of their height, and after rising up to or over the upper open end of said jacket the water overflows and passes down between the jacket *H* and an exterior circular duct or jacket *I*, secured to the upper flue-sheet *f* and extending downward, the same being open at its bottom to or nearly to the level the water *W* should stand in the chamber *C*. Thus the smoke-flues *D* are kept submerged, or mainly so, without choking the steam-space of the boiler, and in case of any falling of the water below its proper level in the lower portion of the steam-chamber *C* the crown-sheet *e* will still be kept flushed with water circulating up the legs *G* and their group of tubes.

Having thus described my invention, what I claim as new, and desire to secure by Letters Patent, is—

1. An upright tubular steam-boiler having its upper water, smoke-flue, and steam space, or part of the boiler adapted to keep the upright smoke-flues mainly submerged from their bottoms upward by the feed-water of the boiler and whereby an overflow of the entering water is supplied to the lower por-

tion of the steam-space of the boiler and the choking of the steam space or chamber of the boiler with water is avoided, substantially as specified.

- 5 2. In upright tubular steam-boilers, the construction and combination of parts, substantially as herein described, consisting of an overflow-feed-water jacket to and inclosing the group of upright smoke-flues open above, to a boiler-feed connection supplying said jacket with water, and an outer jacket within the

steam-space of the boiler, inclosing the overflow-jacket for a portion of its depth and open below for supplying the water overflowing from the first-named jacket down to the 15 lower portion of the outer steam-chamber of the boiler, substantially as specified.

TRUCKSON S. LA FRANCE.
